(57) **CLAIM**

The ornamental design for a battery case, as shown and described.

DESCRIPTION

FIG. 1 is an isometric elevational view of an embodiment of the battery case wherein certain features are shown in broken lines;

FIG. 2 is a front view of the battery case depicted in FIG. 1; FIG. 3 is a rear view of the battery case depicted in FIG. 1; FIG. 4 is a left side view of the battery case depicted in FIG. 1;

FIG. 5 is a right side view of the battery case depicted in FIG. 1;

FIG. 6 is a bottom view of the battery case depicted in FIG. 1;

FIG. 7 is an isometric elevational view of another embodiment of the battery case wherein certain features are shown in broken lines;

FIG. 8 is a front view of the battery case depicted in FIG. 7; FIG. 9 is a rear view of the battery case depicted in FIG. 7; FIG. 10 is a left side view of the battery case depicted in FIG. 7;

FIG. 11 is a right side view of the battery case depicted in FIG. 7; and,

FIG. 12 is a bottom view of the battery case depicted in FIG. 7.

The broken line showing, for example, terminals, terminal identifiers, lids, bases, and support members in FIGS. 1-12 depict an environment for illustrative purposes only and form no part of the claimed design.
